UNITED STATES PATENT OFFICE.

RICHARD K. HOHMANN, OF PERU, INDIANA, ASSIGNOR TO HOHMANN SEWING MACHINE COMPANY, OF PERU, INDIANA.

SEWING-MACHINE TAKE-UP MECHANISM.

1,393,127.

Specification of Letters Patent.

Patented Oct. 11, 1921.

Application filed August 25, 1919. Serial No. 319,723.

To all whom it may concern:

Be it known that I, RICHARD K. HOHMANN, a citizen of the United States, and residing at Peru, Miami county, State of Indiana, have invented certain new and useful Improvements in Sewing-Machine Take-Up Mechanism, of which the following is a specification.

The present invention relates to sewing machines and more particularly to take-up mechanisms for family machines employing large rotary hook mechanism.

The objects of the invention are to provide a smooth acting vibrationless take-up having a throw sufficient to draw up the loop formed by the hook mechanism, said loop being relatively large because the rotary hook mechanism carries a bobbin larger than heretofore; and to provide a compact and simple mechanism adapted to be manufactured at minimum cost and easily assembled in the machine. Other objects and features of novelty will be apparent from the description taken in connection with the drawings in which—

Figure 1 is a front elevation of the head end of a sewing machine frame equipped with the present invention, the head being shown in section;

Fig. 2 is a side elevation of the parts shown in Fig. 1, the usual cover plate on the head being removed;

Fig. 3 is a similar view, the parts being shown in a different position; and

Fig. 4 is a sectional view of a detail taken substantially on the line 4—4 of Fig. 2.

Referring to the drawings the numeral 10 indicates the frame of a sewing machine having the hollow head 11 within which is disposed the take-up mechanism and the means for operating the needle bar. As shown the main shaft 12 has a disk 13 within the hollow head, portions of which are cut away in order to balance the same. This disk has a crank pin 14 projecting from its face adapted to operate the take-up mechanism as will be described hereinafter. Secured to the end of the crank pin 14 is an arm 15 disposed in a plane transverse to the axis of the shaft 12 and having at its free end a crank pin 16 parallel to the pin 14 and disposed with its axis offset from the axis of the shaft 12. A needle bar 17 extends through the head having bearings in

the top and bottom thereof and is operated 55 by a link 18 having one end pivoted on the crank pin 16 and the other end pivotally secured to the needle bar by a pin 19. It will be apparent therefore that rotation of the shaft 12 effects reciprocation of the 60 needle bar 17.

The take-up mechanism of the present invention includes a rock shaft 20 disposed with its axis parallel to the axis of the shaft 12 and in the rear of the needle bar 17 and the presser foot bar 21. In the form of the invention shown the rock shaft 20 consists of a sleeve rotatably mounted on a pin 22 secured in the head 11 of the machine. At one end the rock shaft is provided with a 70 radially projecting lug 23 and a straight bar or arm 24 is secured in the lug as by means of a set screw 25. This arm has a pivotal and sliding connection with the crank pin 14. As shown, a block 26 is pivotally 75 mounted on the pin 14 and this block is formed with a bore 27 transverse to the axis of the pin 14, the bar 24 slidably fitting within the bore 27. Thus as the shaft 12 is rotated the rock shaft 20 is oscillated 80 through the arm 24. Furthermore, this connection is absolutely noiseless and vibrationless at the speeds of family machines. The arm 24 is straight thus eliminating the shocks, noise and vibration due to employing 85 irregular cams and other similar connections between the main shaft and the take-up mechanism. A take-up arm 28 is secured to the rock shaft 20 for rotation therewith and is disposed at the left of the needle 90 bar as viewed in Fig. 1, that is to say, at the side of the needle bar opposite the actuating arm 24. The head 11 is formed with a suitable slot 29 through which the take-up arm 28 projects.

In Fig. 2 the take-up arm 28 is shown at the upper limit of its motion, and in Fig. 3 at the lower end of its stroke. It will be observed that this arm moves from the lower to the upper end of its stroke, that is, 100 from the position shown in Fig. 3 to that shown in Fig. 2 while the main shaft is turning through about 90°, and thus gives a rapid take-up of the thread loop from the hook mechanism. While at the lower end 105 of its stroke, the arrangement is such, that the arm 28 has a substantial dwell or period of practically no movement. This take-up

is principally designed for a machine in which the hook mechanism makes one rotation for each rotation of the main shaft.

Although a specific form of the invention has been described in detail it is to be understood that it is not thus limited but includes modifications and changes which come within the scope of the appended claim.

Having thus described the invention what is claimed as new and desired to be secured by Letters Patent is:

In a family sewing machine having a frame with a hollow head, a main shaft, a needle bar reciprocable in two bearings in the head a rock shaft disposed parallel to the main shaft in rear of the needle bar, a crank pin on the main shaft at the right of the needle bar, a straight actuating arm

movable with the rock shaft, a block rotatably mounted on said crank pin having a bore offset from, and transverse to, the crank pin axis, said arm slidably fitted in said bore, a take-up arm secured to the rock shaft projecting in front of the head and at the left of the needle bar, an arm carried by said pin disposed tangentially to a circle about the axis of said shaft, a second crank pin carried by said arm eccentrically to the axis of the main shaft and substantially 90° from the first pin, and a link connecting the latter crank pin and needle bar, said link movable in a vertical plane between the actuating arm and needle bar.

In testimony whereof I affix my signature.

RICHARD K. HOHMANN.
